UNITED STATES PATENT OFFICE.

JOHN JOSEPH HIGGINS, OF EAST ORANGE, NEW JERSEY, ASSIGNOR TO WESTINGHOUSE LAMP COMPANY, A CORPORATION OF PENNSYLVANIA.

SHUTTLE FEED STEM HEAD.

Application filed September 5, 1922. Serial No. 586,072.

To all whom it may concern:

Be it known that I, JOHN JOSEPH HIGGINS, a citizen of the United States, and a resident of East Orange, in the county of Essex and

5 State of New Jersey, have invented a new and useful Improvement in Shuttle Feed Stem Heads, of which the following is a specification.

This invention relates to the manufacture of electric incandescent lamps and more particularly to apparatus for making lamp stems.

An object of the invention is to provide a device in which the several parts of a stem 15 may be conveniently and expeditiously assembled.

Another object is to provide mechanism adapted to be adjusted to facilitate the position of stem parts in a stem-making machine.

20 A further object is to provide mechanism which may be actuated by the operator in such manner as to reduce the number of manual operations heretofore necessary in 25 the assembly of stem parts.

Stems for electric incandescent lamps include a plurality of work parts which have been consolidated through the agency of heat and pressure. These work parts include a 30 flare tube, an arbor and two leading-in wires and, in lamps of the tipless type, an additional part termed an exhaust tube.

Machines for manufacturing lamp stems are well known in the art and usually comprise, individually, a central hub suitably 35 mounted on a base and provided with arms terminating in hubs in which stem heads are mounted rotatably.

In the present invention, however, the 40 stem heads are rigidly secured at the ends of the arms, since it has been found advantageous to operate with non-rotating heads, thus avoiding the necessity of providing means for permitting the rotation of the heads when positioned for the assembly of work parts. Means are, however, provided 45 for effecting the intermittent rotation of the spider, the usual indexing mechanism being employed to stop the conveyor temporarily 50 at given stations throughout its path of movement.

During the quiescent periods of the conveyor, the stem parts are assembled in one of the heads, during which time heat is being

applied locally to the assembled parts in 55 other heads. Certain portions of the work are thus rendered plastic for a subsequent pressing operation which is performed by jaws suitably provided for this purpose. The several parts of the stem are thus 60 pressed into consolidation.

During the construction of stems for lamps of the tipless type, a current of air is directed down the exhaust tube while the lower portion thereof is being heated for 65 union with the other portions. The air is under pressure and effects a puncture in the wall of the tube for the purpose of affording communication with the interior during the exhaust of the bulb with which the stem 70 is incorporated.

Most of the above described apparatus as, 75 for instance, the conveyor and other cooperating machine elements, are well known in the art and, therefore, are not illustrated. The outline given, however, will afford a more complete understanding of the present invention which consists in an improved form of head for making lamp stems.

My improvement in stem-making machines consists in the provision of a reciprocable member or shuttle which is disposed on the vertical axis of the head. The head may be of the usual type having an upper 80 pair of jaws for securing an exhaust tube and a lower pair of jaws for securing a flare tube. The jaws are operable not only to secure the work parts, but to center them with respect to the axial line of the head.

My improved work-holder or shuttle consists of a central spindle upon which is 85 mounted a sleeve and cap slidable in a suitable bearing. The cap is provided with a seat for a flare tube and an aperture is provided within the shuttle for the reception of an arbor. Pockets are also provided and suitably located to receive the ends of leading-in wires. The shuttle is movable vertically within the head and may be thrust 90 upwardly to such position as would make it convenient for an operator to insert the arbor, seat the flare tube and properly position the leading-in wires, after which the shuttle may automatically move downwardly within the head until the flare tube is 95 positioned in a given relation to the lower pair of jaws, at which time these jaws may be caused to grip the flare tube, and a con-

tinued downward movement of the shuttle may then properly position an end of the arbor with respect to the end of the flare tube.

- 5 An exhaust tube may then be disposed upon the upper end of the arbor, after which the upper jaws automatically close and secure the exhaust tube to maintain it in proper relation to the other work parts. All 10 operations are performed automatically with the exception of the actual insertion of the several work parts by the operator and it will readily be seen that, with my improved support, an operator will have 15 free access to properly and expeditiously dispose the work parts without the exercise of any unusual amount of caution to avoid projecting or heated parts of the stem head.

The invention will be more clearly understood by a reading of the following description and reference to the accompanying drawings in which,—

Fig. 1 is a view, in elevation, of a stem head, partly in section, and showing the 25 improved work-supporting shuttle;

Fig. 2 is a side view of the parts shown in Fig. 1, a portion of the head being broken away to more clearly illustrate other parts;

30 Fig. 3 is an enlarged view of the upper portion of the shuttle, partly broken away;

Fig. 4 is a transverse section of the shuttle taken on line IV—IV of Fig. 3;

35 Fig. 5 is a plan view of Fig. 1, showing the upper jaws in their open positions, the top plate being removed.

Fig. 6 is a transverse section of a head taken on line VI—VI of Fig. 1; and,

40 Fig. 7 is a detail sectional view of a modified form of the upper end of the shuttle constructed to receive and properly align an arbor having a button.

The several work parts which are to be consolidated to form a stem are indicated 45 in the drawing in dotted lines and comprise a flare tube 10, arbor 11, leading-in wires 12 and exhaust tube 13. In the preferred embodiment of the invention, an arbor is employed without a button formed thereon, but the arbor may be provided with a button by later operations as, for instance, when applied to a button-forming and support-wire-inserting machine such as that shown in the copending application of H. D. 50 Madden and J. J. Higgins, Serial No. 556,957, filed April 27, 1922, combined button making and inserting machine, and assigned to the Westinghouse Lamp Company.

60 If desirable, however, arbors 14, having buttons already formed thereon may be employed, in which case, a modified form of the work support may be used, an example 65 of which is illustrated in Fig. 7 of the drawing and will be later more fully described.

The stem head to which my improvement is applied may comprise a standard 15 (Fig. 1) having a stud 16 integral therewith and adapted to be secured by a pin 17, in a hub 18 of an arm 19 which may be one 70 of a plurality of arms of a conveyor; the conveyor being moved intermittently in the usual manner to progress the head from station to station, in accordance with the order of operations.

The standard 15 may include two parallel vertical supporting members 21 and 22, in which a pair of bearing members 23 and 24, respectively, may be suitably secured. Rotatable within the bearing members 23 and 24 are disposed spindles 25 and 26, respectively. The spindle 25 is rotatable in the bearing member 23 and adapted to actuate a pair of exhaust-tube gripping jaws 27 and 28 mounted in a casing or jaw-guide 29 which is secured to the upper end of the bearing members 23 and 24. The spindle 26 is rotatable in the bearing member 24 and may be actuated to operate a lower pair of flare-tube gripping jaws in a casing 30, 80 said jaws being similar to the above mentioned jaws 27 and 28.

A more detailed description of the operation of these jaws and their functions will 90 be given later.

Suitably positioned between the upper ends of the supporting members 21 and 22 and integral therewith, is a bearing or guide 33 in which the work support or shuttle 34 which carries the stem parts may be slidably disposed. The lower portion of the shuttle, which consists of a guide rod 35, extends 100 downwardly and through an axially disposed aperture in the stud 16. Thus, the shuttle may be reciprocated vertically within the head and upon the vertical axis thereof. The shuttle is held from rotation by a pin 31 which extends through the upper portion of the stud 16 and engages a longitudinal slot 32 provided in the rod 35.

The shuttle 34 may comprise the aforementioned guide rod having a sleeve 36 fastened adjacent the upper end thereof, over which is firmly secured a cap or thimble 37. The rod 35 extends above the thimble 37 115 and is provided throughout the greater part of its length with a groove 38 in which an adjustable stop member 39 is disposed. This member may normally be secured in a given position by a set screw 41 and is adjusted, with respect to the upper end of the groove 38, to provide a space of a given length for the reception of the arbor 11.

An aperture for the retention of an arbor being thus provided, the length thereof may be varied by an adjustment of the stop member 39 to accommodate and properly position arbors of different lengths in accordance with the type of lamp in which the stem is to be used.

For the proper disposition of the leading-in wires 12, the guide-rod 35 is provided with additional longitudinal grooves 42 and 43 at opposite sides thereof, each of these grooves being spaced approximately 90° about the axis of the guide-rod 35, from the groove 38. The grooves are of shallow depth at the upper end of the guide-rod but the lower portion of the rod, being of an increased diameter, permits an increase in the depth of the grooves, and movable stops 44 and 45 are disposed therein and are held in any given position by set screws 46 and 47. The stop members 44 and 45 will be termed the lead-stops and may be adjusted by a manipulation of the screws 46 and 47 to vary the length of the apertures in which the leading-in wires are inserted, such apertures being commonly termed pockets. It will thus be seen that various lengths of leading-in wires may be inserted and their relative position with respect to the arbor may be changed in accordance with the construction of the particular type of lamp in which the stem is to be used. The upper surface 48 of the cap 37 is suitably formed to constitute a seat for the end of a flare tube 10, when applied to the shuttle and disposed over the end of the guide rod 35. It will thus be evident that the arbor, flare tube and leading-in wires may be applied to the shuttle preparatory to their final relative positions when assembled for consolidation. The loading of the head with these stem parts is therefore greatly facilitated since the shuttle may be moved to its upper position as shown in Fig. 1 and the several stem parts may be disposed thereon and between the jaw 27 and 28 which are open while the head is in the loading position.

During the disposition of the stem parts, the shuttle is held in its upper position by reason of the engagement of its lower end 49 with a cam surface 51.

A spring 52 is disposed between a collar 53 secured to the guide-rod 35 and the lower end of the stud 16 and serves to normally urge the shuttle downwardly to its lower position. The shuttle may be permitted to fall by reason of its weight, if desired, the spring, however, being provided to give a more positive action.

As the stem head is moved by the conveyor, and the cam surface 51 moves the shuttle to its upper position, other laterally disposed cam surfaces 54 and 55 (Fig. 6) engage arms 56 and 57 secured to the lower ends of the spindles 25 and 26, respectively, and operate to open the jaws. Each pair of jaws is normally maintained closed through the torsional action of helical springs 58 and 59 (Fig. 1) disposed respectively between the upper surface of the arms 56 and 57 and collars 61 and 62 which are secured

to the bearing members 23 and 24, respectively.

One end of the spring 58 is secured to the arm 56 and the other end is secured to the collar 61, thus, as the arm is moved, the spring is placed under tension and its recovery serves to close the jaws; the spring 59 is similarly attached with a like resultant action since the upper and lower jaws, mounted in jaw-carriers 29 and 30, respectively, are similar. A description of the upper jaws and actuating mechanism as shown in Fig. 5 will answer for both.

As the spindle 25 is oscillated, a toothed segment member 63, secured at the upper end of the spindle, is also oscillated. One side 64 of the segment engages a rack 65 on an arm 66 secured to the jaw 28 while the other side 67 engages a rack 68 secured to the jaw 27. The jaws are slideable in the casing 29 between guides 71 and 72. It will thus be seen that a movement or oscillation of the cranks or arms 56 and 57 will cause an opening and closing of the jaws and that the cam surfaces 54 and 55 may be positioned to open the jaws and subsequently release them for closure through the action of the springs 58 and 59.

After the flare tube, arbor and leading-in wires have been positioned on the shuttle and the head is moved with the conveyor, the cam surface 51 permits the shuttle to drop when it reaches a predetermined position, to bring the flare tube to the desired location, as indicated in Fig. 2, the arm 57 is permitted to move by reason of the receding cam surface 55 and the lower jaws thus close upon and secure the flare tube. The shuttle, however, continues to move downwardly to its lowest position at which it is stopped by the engagement of a collar 73 secured to the guide-rod 35, with the upper portion of the casting which is integral with the stud 16. The operator, at this point, inserts the exhaust tube 13 into the flare tube 10 in such position that it either rests upon, or is positioned slightly above, the upper end of the arbor 11, the insertion of the exhaust tube being accomplished just as the cam surface 55 recedes to permit the closure of the jaws 27 and 28 of the upper jaw carrier or casing 29.

After the parts are properly assembled, the head is carried into position for the local heating of the parts by means of suitable fires 74 which are indicated in dotted lines in Fig. 2. After the parts have been suitably heated, pressure is applied to the heated portion, for which purpose a pair of press jaws 75 and 76 are pivotally mounted on pins 77 and 78 that are suitably disposed in bearings on opposite sides of the standard 15. The jaws 75 and 76 are also provided with off-set portions or arms 81 and 82, respectively, which are connected

by links 83 and 84 to push-rods 85 and 86 which, in turn, are secured to a cross-head 87. The push-rods 85 and 86 are guided in bearings 88 and 89, and the cross-head 87 is movable longitudinally of the stud 16. A reciprocation of the cross-head will, therefore, effect a transmission of motion to the jaws 75 and 76.

The jaws are normally maintained in open position by the expansive action of a spring 91 disposed between the cross-head and the lower side of the hub 18 and may be actuated in the usual manner, as, for instance, by the lever arm 92 shown in dotted lines in Fig. 1 which illustrates, diagrammatically, a lifting member which may make contact with the set screw 93 of the cross-head 87 and lift it in opposition to the spring 91 for the purpose of closing the jaws 75 and 76 to press the heated portion of the stem parts.

Where it is desirable to use an arbor having a button formed thereon, the upper end of the guide rod 35 may, as shown in Fig. 7, be provided with a resilient member 94 which may make contact at one side of the arbor and hold it firmly against a boss or enlarged portion 95 of the guide to maintain the axial line of the arbor and that of a guide-rod 35 in coincidence.

In operation, the head moves with the conveyor toward an operator at which time the shuttle is raised to the loading position, and the cam surfaces 54 and 55 actuate the lever arms 56 and 57 to open both the upper and the lower pairs of jaws. The operator then has free access to the upper end of the shuttle and inserts an arbor 11 into the aperture provided. A flare tube is then placed over the upper end of the guide-rod and seated on the surface 48 of the cap 37, and leading-in wires are properly positioned by insertion into their respective pockets. The head is then permitted to move in its path with the conveyor and, as the head advances, the shuttle drops, carrying the positioned stem parts.

Before the parts reach the lower position of the shuttle, however, the lower pairs of jaws carried in the jaw-carrier 30 close upon the flare tube and secure it. At the same time, the shuttle continues its downward movement until it reaches its lowest position which brings the upper end of the arbor 11 in proper relation to the lower end of the flare tube. During this movement, the head has not advanced sufficiently to be out of reach, and the operator inserts an exhaust tube which is subsequently gripped by the upper jaws carried in the jaw-carrier 29 and maintained in proper relation to the arbor and the flare tube. The head may be then advanced to the position at which the jaws 74 render the portions of the flare tube, arbor and exhaust tube suitably plastic, at

which time the head is in operative relation to any suitable mechanism, such as the lever 92, which may make contact with the set screw 93, thus moving the cross-head upwardly and causing the jaws 75 and 76 to compress and consolidate the glass-stem parts. A current of air is then directed down the exhaust tube to puncture the wall which consists of the fused flare tube and exhaust tube, thus completing the stem, in so far as the operations to be performed in the stem-head are concerned. The operation of blowing the hole for the exhaust tube is, however, known in the art and, as it is not a part of the present invention, has not been illustrated.

The head may then be advanced until it again reaches a position convenient to an operator, at which time the jaws automatically open and the shuttle moves upwardly to bring the stem in position for convenient removal and to permit of rapid and easy reloading.

Although a preferred embodiment of the present invention is shown and described, it is to be understood that other modifications may be made therein without departing from the spirit and scope of the appended claims.

What is claimed is:

1. A stem head comprising a reciprocable member, means carried by said member for supporting stem parts and means for moving said member to a position for the convenient positioning of said parts. 95

2. A stem head comprising a movable member axially disposed within said head, a work-part support carried by said member and means for moving said member axially of said head to locate said support in a position convenient for the disposition of said part on said support. 100

3. A stem head comprising a member slidably associated with said head, lamp part supporting means carried by said member 110 and means for moving said member to position said supporting means for the convenient positioning of lamp parts thereon.

4. A stem head comprising a reciprocable member axially disposed within the head, means carried by said member for supporting a plurality of lamp parts and means for moving said member to change the relative positions of said member having lamp parts supported thereon and said head. 115

5. A stem head comprising a slidable member, a seat carried by said member to receive a flare tube, an aperture in said member to receive an arbor and means for moving said member to position to facilitate the positioning of said tube and arbor in said aperture. 120

6. A stem head comprising a shuttle, means carried by said shuttle for supporting a plurality of stem parts and means for 125

- actuating said shuttle to position the same for the disposition of said stem parts thereon.
7. A stem head comprising a shuttle, said shuttle having a seat for a flare tube, an aperture for an arbor and pockets for leading-in wires, and means for moving said shuttle to a given position with respect to said head for the convenient disposition of 10 said tube, arbor and wires.
8. A stem head having means for supporting an exhaust tube, a shuttle movably disposed in said head for carrying an arbor and flare tube, and means for moving the 15 shuttle to position for the convenient assembly of the said arbor and flare tube.
9. A stem head comprising a shuttle movable in said head, means carried by said shuttle for supporting a flare tube and an 20 arbor, means for gripping said flare tube and means for moving said shuttle to position an end of said arbor in a given relation to an end of said flare tube.
10. A stem head comprising a shuttle 25 movable in said head, means carried by said shuttle for supporting a flare tube and an arbor, means for gripping said flare tube and means for moving said shuttle to position an end of said arbor in a given relation 30 to an end of said flare tube, and means for supporting an exhaust tube in a given relation to said arbor.
11. A stem head having a pair of tube-gripping jaws, a shuttle associated therewith, said shuttle having a seat for a flare tube, and an aperture for an arbor and means for actuating said shuttle to position 35 said tube for engagement with said jaws and means for operating said jaws to engage said tube.
12. A stem head having a shuttle for carrying several parts of a stem, said shuttle having associated therewith a seat for supporting a flare tube, an aperture to receive 40 an arbor, and pockets for the reception of leading-in wires, means for moving said shuttle in one direction for the positioning of said flare, arbor and wires, means for moving the shuttle in an opposite direction 45 to a given position, means for gripping said flare, means for continuing the movement of said shuttle to effect the removal of said flare from said seat to position one end of said flare in a given relation to an end of 50 said arbor.
13. A stem head having a shuttle for carrying several parts of a stem, said shuttle having associated therewith a seat for supporting a flare tube, an aperture to receive 55 an arbor, and pockets for the reception of leading-in wires, means for moving said shuttle in one direction for the disposition of said flare, arbor and wires, means for moving the shuttle in an opposite direction to a given position, means for gripping said flare, means for continuing the movement of said shuttle to effect the removal of said flare from said seat to position one end of 60 said flare in a given relation to an end of said arbor, and means for supporting an exhaust tube in a given relation to said flare and arbor.
14. A stem head comprising a reciprocable member adapted to support a plurality of lamp parts, means for moving the member to position the said lamp parts, and means for gripping and holding the parts in a desired relation for consolidation.
15. A stem head comprising a reciprocable member adapted to support a plurality of lamp parts, means for moving said member to position the said parts in given 70 relation to each other, means for gripping and holding the parts for consolidation and means for releasing said parts.
16. A stem head comprising a reciprocable member adapted to support a plurality of lamp parts, means for moving said member to position said parts in a given relation, means for gripping said parts to 75 maintain them in desired relative positions, means for rendering plastic a portion of said parts and means for compressing said plastic portion to consolidate said parts.
17. A stem head comprising a reciprocable member adapted to support a plurality of lamp parts, means for moving said member to position said parts in a given relation, means for gripping said parts to maintain them in desired relative positions, means for rendering plastic a portion of 80 said parts, means for compressing said plastic portion to consolidate said parts and means for releasing said parts after consolidation.
- In testimony whereof, I have hereunto subscribed my name this first day of September, 1922.

JOHN JOSEPH HIGGINS.
